UNITED STATES PATENT OFFICE

2,587,547

WINDOW CONSTRUCTION

George Steingruber, Atlanta, Ga.

Application September 23, 1946, Serial No. 698,751

3 Claims. (Cl. 189—76)

1

The present invention relates to window constructions, and more especially to metal window structures of the double-hung sash type.

The primary object of the invention is to provide a simple, durable, rigid, and economical window construction which may be made from flat sheet-metal stock from which the component parts may be stamped and formed preliminary to assembly thereof into a complete unitary structure, ready for installation. In attaining the foregoing objective as applied to window structures of the double-hung sash type, each sash is preferably composed of two complementary stampings, each stamping of which is in one piece and forms one-half of the sash, that is, an inner section and an outer section, said sections telescoping one within the other and being secured together by suitable fastenings extending through the overlapping marginal edges thereof.

A further object of the invention is to provide a sheet metal window construction embodying double-hung sashes which balance each other, and which are provided with operating means such that raising of the lower sash automatically and simultaneously causes lowering of the upper sash, and vice versa; said operating means preferably including rack means on each sash and a pinion operatively engaging the rack means on each sash and establishing a connection therebetween for causing simultaneous movements thereof and balancing of the sashes with respect to each other.

Another object of the invention is to provide a sheet metal window construction of the double-hung sash type, wherein the sashes are slidably mounted for vertical movement in channels formed by the window frame, said frame having a parting strip detachably connected to the inner face of the frame at each side thereof and projecting between the sashes, and a one-piece sheet metal weather strip mounted on the inner face of each side of the frame and clamped between the frame and the parting strip aforesaid, with the weather strip extended at opposite sides of the parting strip for cooperation with each sash.

A still further object of the invention is to provide a sheet metal window construction of the double-hung sash type, in which the sashes are provided with a simple and improved adjustable locking means for securely locking the sashes in closed position, and which may be easily and quickly adjusted to cause the sashes to tightly engage the top and bottom, respectively, of the window frame when the sashes are locked.

2

Yet another object of the invention is to provide a metal window sash which may be stamped out from flat sheets and is composed of two complementary, one-piece, rectangular sections, the outer marginal edges of which have a sliding fit, one over the other, the inner margin of one section being formed with a shoulder to provide a seat for the window glass, and the inner margin of the complementary section being laterally offset towards the shoulder aforesaid so as to tightly abut the glass and firmly secure the glass in its seat, with the glass firmly clamped between the complementary sections.

Other and further objects and advantages of the invention will be hereinafter described and the novel features thereof defined by the appended claims.

In the drawings:

Figure 1 is a view in elevation of a metal window structure of the double-hung sash type constructed in accordance with the present invention, with portions thereof broken away and shown in section;

Figure 2 is a vertical sectional view taken centrally through the window structure on the line 2—2 of Figure 1, and particularly showing the details of the adjustable sash lock;

Figure 3 is a fragmentary horizontal sectional view taken on the line 3—3 of Figure 2;

Figure 4 is a fragmentary horizontal sectional view taken on the line 4—4 of Figure 1, and showing the latch for securing the sashes in selected positions of vertical adjustment;

Figure 5 is a composite view in vertical section through one of the sashes, showing the component parts related to each other according to their cooperative relationship on final assembly; and

Figure 6 is a composite view in horizontal section through the sash of Figure 5.

While the invention will be particularly described herein as applied to a double-hung window construction, it is to be understood that it is not confined thereto inasmuch as certain features of my invention are applicable to other types of window constructions as will be readily understood by those skilled in the art.

According to one of the principal characteristics of the present invention, the window frame 1, and the two sashes 2 and 3 are so designed as to be capable of being made from sheet metal such as aluminum, or other suitable metallic material, the component parts of the window structure being stamped out from flat sheet stock by

any suitable method or methods commonly practiced in the sheet metal art.

The window frame 1 may be of any suitable construction, but is preferably formed of spaced side members 4, 4 arranged in upright parallel relation to each other, and a cross member 5 disposed horizontally and joining the top ends of the side members 4, 4, these members each being made of sheet metal and preferably having the form of channels. The lower ends of the side members 4, 4 are connected together by a horizontally disposed member 6 which is also made of sheet metal and is shaped in the form of a sill, said sill 6 being arranged parallel to the member 5 which is commonly known as the head member. Attached in any suitable manner to the members 4, 4 and the member 5, at the inside and outside respectively of the frame 1, are plates designated 7 and 8, respectively, which extend inwardly from these members for a short distance so as to over-hang the window opening defined within the frame members 4, 4 and 5. The inwardly projecting extensions of these plates consequently serve the purpose of stop strips, as will hereinafter be more fully understood.

Each of the members 4, 4 and 5 is provided at its center with a longitudinally extended groove or recess 9 in which is adapted to be seated a parting strip 10, said parting strip extending upwardly from the sill 6 at each side of the window frame, to the head member 5, and across the head member between the two side members 4, 4. The parting strip 10 preferably has the form of an inverted U-shaped channel made of sheet metal, and is attached to the members 4, 4 and 5 in any suitable manner, as by means of screw fastenings 11 arranged at spaced intervals along the parting strip. By having the parting strip 10 seated in the recess 9 formed in the members 4, 4 and 5, the parting strip will always be accurately positioned on assembly of the window structure, and may be removed and replaced in the same position should it become necessary to remove the parting strip.

It will be understood from the foregoing that the parting strip 10 cooperates with the plates 7 and 8 on opposite sides of the window frame 1 to form two channels in the window frame, one of said channels lying at one side of the parting strip and slidably receiving therein the sash 2, and the other channel lying at the opposite side of the parting strip, and slidably receiving the sash 3. The sashes 2 and 3 are substantial duplicates of each other, and their construction will be best understood from reference to Figures 5 and 6 of the drawings.

As shown in Figures 5 and 6, each sash is made up of two complementary sections respectively designated 12 and 13, both sections being preferably stamped out in one piece from flat sheet metal stock and having special cross sectional shapes for seating a window glass within the sash, and for insuring rigidity of the sash when the two sections 12 and 13 are assembled together. Both sections 12 and 13 are generally rectangular in outline, and the section 12 is provided with a flat vertically disposed face 14, from the outer margin of which extends a flange 15 disposed perpendicular to the face 14 and running all the way around the sash section. From the inner marginal edge of the vertical face 14, the metal section 12 is inclined inwardly at an acute angle relative to the horizontal axis, and then is reversely bent outwardly in parallel rela-

tion to the face 14, and finally bent again to form a flange 19 disposed parallel to the outer marginal flange 15. This formation forms a shoulder 16 against which the window glass 17 may be seated, together with an interposed gasket or weather strip of rubber or other suitable flexible material, designated 18, or in lieu of said gasket or weather strip, conventional glazing putty may be used to seal the window glass 17 in its seat defined by the shoulder 16. At the base of the shoulder 16, the flange 19 serves to centralize the gasket 18 and the window glass 17 in the sash section 12, said flange 19 preferably being interrupted at the corners of the sash, but except for such interruptions, extending completely around all four sides of the sash section 12.

The complementary sash section 13 includes a vertically disposed face 20 from the outer margin of which a flange 21 is extended at right angles to said face 20, said flange 21 being continued all the way around the four sides of the section 13. The section 13 is made slightly larger than the section 12 so that the two sections may be pressed together with a tight friction fit by telescoping the flange 21 of section 13 over and around flange 15 of section 12. From the inner margin of the vertical face 20 of the sash section 13, the metal is extended inwardly on a smooth curve as indicated at 22, forming a pressure or clamping rim which is adapted to firmly abut against the window glass 17 as the sash sections 12 and 13 are pressed together with the window glass 17 disposed therebetween, as indicated in broken lines in Figure 6 of the drawings, so that on final assembly of the complementary sash sections, the window glass will be firmly clamped between the rim 22 and the shoulder 16 of the respective sash sections.

After pressing the sash sections 12 and 13 together in the manner previously described, U-shaped channel members 23 and 24 are pressed over the vertical sides of the sash and secured thereto by suitable fastenings, preferably of the screw type, as indicated at 25, said screw fastenings penetrating through the channels 23 and 24, and through the overlapped flanges 15 and 21. The sash sections are thus positively locked together, and although the sash would be completely rigid by reason of the special shape of the respective sash sections, such rigidity is still further assured by the use of the channel members 23 and 24 which are applied to the opposite vertical sides of the sash.

In the case of the upper sash 2, as shown in Figure 2 of the drawings, the upper horizontal bar of the assembled sash is preferably provided with a sealing strip of rubber or other suitable flexible material, said sealing strip being designated 26 and being substantially L-shaped in cross section, with one arm 27 interposed between the overlapping flanges 15 and 21. To accommodate the arm 27 of the sealing member 26, the flange 21 along the top of the sash is preferably outwardly offset slightly, as indicated at 28, and screws 29 arranged at spaced intervals are screwed through the flanges 15 and 21, and through the intervening arm 27 of the sealing member 26, to positively clamp the parts together.

A similar sealing strip 30 is provided along the bottom edge of the lower sash 3, said sealing strip being secured in position by screws 31 extending through the overlapped flanges 15 and 21, the latter of which is offset as at 32 to accommodate the interposed arm 33 extending from the body of the sealing member 30.

The lower horizontal bar of the upper sash 2, and the upper horizontal bar of the lower sash 3 are respectively provided with meeting rails designated 34 and 35, said meeting rails being attached to the respective bars in any suitable manner, by means of screw fastenings 36 and 37 which are arranged at spaced intervals along the bars, and penetrate through the meeting rails and through the overlapped flanges of the respective sash sections, as clearly shown in Figure 10 of the drawings. The meeting rails are preferably formed of sheet metal and are duplicates, one of the other, but arranged in reversed relation as clearly shown in the drawings. Each meeting rail includes an elongated horizontal portion 38 which is bent over at right angles at one end, as indicated at 39 to hook over the sash bar to which it is attached, and at the opposite end, the portion 38 is reversely bent upon itself at an acute angle to form an inclined face 40 which is adapted to abut against the corresponding face of the meeting rail on the other sash, when the sashes are closed. The free edges of the inclined portions 40 of the respective meeting rails are further bent inwardly towards the sash so as to lie substantially parallel to the portions 38, as indicated at 41, the extreme edges of the portions 41 abutting against the corresponding faces of the respective sashes.

When the sashes are assembled in their complete forms, and mounted in the window frame at opposite sides of the parting strip 10, they are free to slide vertically in the conventional manner of double-hung sashes. Being made of sheet metal, they will always operate freely and smoothly in the window frame as the sashes are raised and lowered. If desired, suitable weather strips may be provided at opposite sides of the sashes to prevent air from passing around the sashes between their vertical edges and the vertical sides of the window frame. Owing to the special construction of my new window structure, an exceedingly simple and efficient weather strip may be employed in the form of a single sheet of relatively thin metal formed in one piece and disposed across the entire face of each side of the window frame, as illustrated in Figure 3 of the drawings. As shown in this figure, the weather strip is designated generally at 42, and has its central part seated in the channel or recess 9 of the window frame, and clamped firmly in position by the parting strip 10 which is drawn up tightly against the weather strip by means of the screws 11 which serve to secure the parting strip to the opposite sides of the window frame. At each side of the parting strip 10, the weather strip 42 is preferably bowed inwardly as indicated at 43 and 44, respectively, so as to make good contact with the vertical edges of the window sashes. The weather strip 42 may be made of any suitable material commonly employed for such purposes, and preferably of a material which is inherently resilient so as to insure a sealing contact between the weather strip and the window sashes in all positions of the sashes.

If desired, the sashes 2 and 3 may be equipped with operating means such as will cause simultaneous movement of both sashes on moving either sash, and at the same time serving to balance the sashes with relation to each other. For this purpose, the inner edges of the channel members 23 and 24, respectively, of both sashes are provided with a series of teeth 45 extending the full length of each channel member, said

teeth forming racks which mesh with pinions 46 fixed to the window frame at the respective opposite sides of the frame, and located between the sashes 2 and 3. While only one pinion at one side of the window frame is shown in the drawings, it is to be understood that two pinions are preferably employed, one located at each side of the window frame, which are duplicates of each other. As will be seen from reference to Figures 1 to 3 inclusive, each pinion is rotatably mounted on a fixed stud or pin 47 which is suitably secured to the window frame in any desired manner, as by means of a clamping nut 48, said stud or pinion extending through the window frame 4, through the weather strip 42, and through the parting strip 10 to the inside of the latter, and projecting sufficiently beyond the inner face of the window frame to receive the pinion thereon. The parting strip is cut away to allow the pinion to project therethrough so as to mesh with the racks 45 on the sashes at opposite sides of the parting strip, leaving sufficient clearance around the pinion so that it is free to rotate without binding against the parting strip 10. By employing two pinions located respectively at opposite sides of the window frame, the sashes will always be perfectly balanced, and will always work freely in their raising and lowering movements in the window frame, without binding in the channels in which they slide, and the pinions 46 are preferably located with their central axes lying in a plane which extends horizontally through the middle of the lower horizontal bar of the upper sash and the upper horizontal bar of the lower sash. Thus the pinions will always be in engagement with the toothed racks on both sashes in all positions of the sashes. With such an arrangement, when the lower sash 3 is raised, the upper sash 2 will be lowered a corresponding amount, and vice versa. To facilitate such raising and lowering movements of the sashes, the lower sash may be equipped with lifts or hand-holds (not shown), which may be either attached thereto as a separate element, or which may be formed integral therewith as by stamping the metal of the sash in an obvious manner.

In order to secure the sashes against movement when shifted to a fully or partially opened position, I preferably provide latch means which is selectively operable to positively restrain the sashes against movement in the various positions of adjustment thereof. Such latch means may have any suitable form, such as the simple form illustrated in the drawings, reference being particularly made to Figures 1 and 4 in which 50 designates a latch member pivotally mounted at 51 upon the top of the upper bar of the lower sash member 3, said latch member being disposed at one side of the sash, near the parting strip 10 and having a pin 52 projecting therefrom towards the parting strip and selectively receivable in a series of spaced openings 53 formed in the parting strip, as shown clearly in Figure 1. The latch member 50 is rockable in opposite directions in a horizontal plane about a vertical axis so that the pin 52 may be selectively engaged in or withdrawn from the openings 53 in the parting strip 10, at will, by manual manipulation of the latch member in an obvious manner. If desired, the latch member may be equipped with a spring 54 which either biases the latch member towards a position automatically engaging the pin 52 with the openings 53, or, in the alternative, which imposes sufficient frictional resistance to rocking movement of the latch member as to cause the latch member to remain

in any position to which it is manually shifted, after assuming such position. By the use of such a latch member as above described, the sashes may be securely and positively restrained against movement while in a partially or fully opened position, and since the latch member is only readily accessible from the inside of the window structure, unauthorized entry through the window or unauthorized movement of the sashes by a person or persons outside of the window, is prevented.

I also preferably provide an improved lock means for positively locking the sashes in their fully closed position, said lock means being best illustrated in Figures 1 and 2 of the drawings. Referring particularly to such lock means, there is attached to the lower horizontal bar of the upper sash 2 a flat plate 55 which is secured to the inner face of the bar in any suitable manner, as by means of screws 56, said plate being disposed at or near the mid-portion of the sash and extending upwardly from the lower bar to a point somewhat above the same where it terminates in a hook-shaped extremity 57. As will be seen in Figure 2, the lower portion of the plate 55 is concealed within the meeting rail 34, except for the upper hook-shaped portion 57 which extends above the meeting rail, and the meeting rail is preferably notched or cut-out in the zone of the plate 55 so that the horizontal portion 41 of the meeting rail will abut against the lower bar of the upper sash except in the zone of the plate 55. 3

Attached to the upper side of the lower sash 3 and pivotally mounted thereon is a rotatable lock member generally designated 58, said lock member 58 including a flat base 59 from which extends upwardly at an inclination thereto a marginal cam wall 60 of varying height and comparable to lock members heretofore used extensively for locking double-hung windows. The cam wall 60 extends about the flat base 59 for a distance of approximately 180 degrees and terminates at one end in an offset finger piece 61. At the center of said base 59 and extending upwardly therefrom is an enlarged head 62 which is somewhat dome-like in shape, said head being preferably formed as an integral part of the base 59 and cam wall 60. The dome-like head 62 is counterbored and interiorly threaded to threadedly engage the upper extremity of an upright threaded stud or pin 63 which is rigidly secured to the lower sash 3 at its mid-portion and extends upwardly therefrom. The stud or pin 63 is anchored to the sash in any suitable manner, as by means of a pair of clamping nuts 64 and 65 located respectively above and below the elongated horizontal portion of the meeting rail 35 which is carried by the upper end of the lower sash 3. The base 59 and the lower end of the dome-like head 62 are recessed as at 66 to clear the nut 64 and permit the lock member 58 to be freely rotated on the stud or pin 63. This has the advantage, and distinguishes from former window locks heretofore used by permitting quick adjustment of the lock member 58 in an upward and downward direction so as to raise or lower the cam wall 60, as the case may be, as required to force the upper sash 2 and the lower sash 3 into firm engagement with the top and bottom respectively of the window frame 1, when the sashes are fully closed and locked. The adjustment is very simple and may be quickly made when the sashes are in partially open position, by merely unscrewing the lock member 58 in one direction or screwing it up in

the other direction relative to the threaded stud or pin 63 with which the lock member 58 is threadedly engaged.

In the use of window structures of the type above described, and particularly when the sashes are stamped out in the form of complementary telescopic sections, each of which is in one piece, the cross sectional dimensions of the top, bottom, and side bars which form the sash units may be reduced to a minimum without material sacrifice of rigidity and durability, and considerably less than the cross sectional dimensions required for sashes made of wood or extruded metal shapes. Thus, my improved window construction presents a substantially greater area of glass for windows of standard size. In addition, square corners at the junctions of the top, bottom, and side bars may be avoided by rounding these corners in stamping out the sash sections in one piece, thereby making the cleaning of the window glass easier and eliminating accumulations of dirt and other spotty conditions which are common in windows of conventional construction with square corners. My new window construction is adaptable for installation in buildings and other structures of widely varying types, and may be installed with a minimum of effort and expense by the use of simple anchors of any suitable type. Other advantages will be readily apparent to those skilled in the art, and hence such advantages need not be further described.

While the specific details have been herein shown and described, the invention is not confined thereto as changes and alterations may be made without departing from the spirit thereof as defined by the appended claims.

I claim:

1. A metal window sash construction comprising a pair of one-piece complementary sheet metal stampings of rectangular outline, said stampings each having an outer marginal flange extended completely about the extreme outer marginal edges thereof and at a right angle thereto, with the flange of one stamping overlapping the flange of the other stamping, a pair of channel members in which said overlapping flanges are seated, said channel members extending the full length of said sash on the respective opposite sides thereof, means for securing said overlapping flanges in said channel members, and a transparent pane mounted in the sash and clamped between the complementary stampings.

2. A window sash, comprising a pair of complementary sheet metal frames, each of generally rectangular one-piece form, each of said frames having outer marginal flanges extending completely therearound and disposed at a right angle thereto and slidably engaging one within the other and secured together about the periphery of said frames, one of said frames having a preformed shoulder extending about its inner margin against which a window pane is seated, and the other complementary frame having a flange inwardly offset therefrom towards the shoulder aforementioned and extending about the inner margin of the frame for abutting engagement with the window pane when the latter is disposed between the shoulder on one frame and the offset flange on the other frame, the frame having the shoulder being provided with a further flange extending about the inner margin thereof from the base of the shoulder towards the other frame in parallel relation to the slidably engageable flanges about the outer

margins of the frames, said further flange terminating in abutting engagement with the other complementary frame and extending about the marginal edges of the pane when the pane is mounted in the sash as aforesaid.

3. A window sash as defined in claim 2, wherein at least two opposite edges of the assembled sash frames are seated in channel members which are extended the full length of the frames and rigidly secured thereto.

GEORGE STEINGRUBER.
